(57) **CLAIM**

The ornamental design for a golf training device, as shown and described.

DESCRIPTION

FIG. 1 is a front right perspective view of a golf training device showing my new design;

FIG. 2 is a top plan view thereof;

FIG. 3 is a front elevation view thereof;

FIG. 4 is a rear elevation view thereof;

FIG. 5 is a bottom plan view thereof;

FIG. 6 is a right side elevation view thereof;

FIG. 7 is a left side elevation view thereof;

FIG. 8 is a front right perspective view of a second embodiment of the golf training device of FIG. 1;

FIG. 9 is a top plan view thereof;

FIG. 10 is a front elevation view thereof;

FIG. 11 is a rear elevation view thereof;

FIG. 12 is a bottom plan view thereof;

FIG. 13 is a right side elevation view thereof; and,

FIG. 14 is a left side elevation view thereof.

The broken lines showing in the attached drawings are for illustrative purposes only and form no part of the claimed design.
